UNITED STATES PATENT OFFICE.

CHARLES PHILO MOSHER, OF GROTON, NEW YORK, ASSIGNOR TO CORONA TYPEWRITER COMPANY, INC., A CORPORATION OF NEW YORK.

TYPE-WRITING MACHINE.

1,269,202.

Specification of Letters Patent. Patented June 11, 1918.

Original application filed October 16, 1915, Serial No. 56,242. Divided and this application filed November 27, 1915. Serial No. 63,737.

To all whom it may concern:

Be it known that I, CHARLES PHILO MOSHER, a citizen of the United States, and a resident of Groton, county of Tompkins, 5 and State of New York, have invented certain new and useful Improvements in Type-Writing Machines, of which the following is a full, clear, and exact description.

This invention relates more particularly 10 to the escapement mechanism of foldable visible or front-strike typewriting machines in which the keys of the keyboard may be brought into close relation to the platen to make the machine compact when not in use, 15 and is a division of my application Serial No. 56,242, filed October 16th, 1915.

One of the principal objects of the invention is to provide a typewriting machine in 20 which a universal or standard keyboard may be employed and in which the escapement mechanism for letter spacing the carriage may be operated by the keys of the keyboard and the entire keyboard and key action folded with respect to the platen to place the 25 keys in compact relation to the platen without disturbing the coöperative relation between the keys and the escapement mechanism.

Another object of the invention is to provide a foldable support on which is mounted 30 the type-bars and a universal or standard keyboard having individual keys for operating individual type and wherein the pivotal part of the foldable support may serve as 35 a connecting means between the keys and the escapement mechanism for the platen carriage in order that no break or disconnection is necessary whether the machine is in a folded position or in an unfolded position.

A further object of the invention is to provide a simple and efficient rotary escapement mechanism for a foldable typewriter in which the said escapement mechanism 45 and the platen carriage are maintained in the same operative relation both when the machine is in a folded position and when in an unfolded position.

A still further object of the invention is 50 to provide simple and efficient connecting means between the escapement mechanism and the keys of the keyboard of a foldable typewriter.

A still further object of the invention is to provide a typewriting machine in which 55 the escapement mechanism and the parts operating the same are of simple construction and may be readily made and assembled.

With these and other objects in view, the invention will be hereinafter more particularly described, with reference to the accompanying drawings, which form a part of this application, and will then be pointed out in the claims at the end of the description.

In the drawings, Figure 1 is a longitudinal section of one form of machine embodying the invention, showing a construction wherein the entire mechanism of the machine may be inclosed within the carrying case which may form a frame or support for the typewriter mechanism.

Fig. 2 is a vertical section taken on the line II—II of Fig. 3.

Fig. 3 is a vertical transverse section 75 taken on the line III—III of Fig. 1, the type-bars and parts of the key action being removed.

Fig. 4 is a vertical longitudinal section, partly in elevation, showing parts of the machine in a folded compact condition.

Fig. 5 is a sectional plan view with parts of the machine removed, showing the means whereby on the operation of the universal bar the escapement dogs may be operated; 80 and

Fig. 6 is a fragmentary section of a part of the connecting mechanism between the foldable parts, showing how the escapement mechanism may be operated without any 90 disconnection whatever between the universal bar and the escapement mechanism.

While the invention is shown as applied to a typewriter in which an inclosing case is employed, it will be understood that the 95 folding principle between the key-operated levers and the escapement mechanism may be embodied in a machine in which an ordinary or any preferred form of frame may be employed or a frame independent of such 100 case, and that said foldable principle as well as the construction of the escapement and operating means therefor may be employed in typewriters of various constructions.

The casing 10 has a main member 11 and 105 a top member or cover 12 which is hinged

2 at 13 to said main member 11. At the forward lower edge of the main member 11 is a foldable member 14 which is pivoted or hinged at 15 to said main member 11 so that said member 14 may be folded upwardly and when so folded and the cover 12 thereon moved over and forward as shown in Fig. 4, a substantially uniform and regular inclosing case is provided. This member 14 may be held in its open position by means of stays 16 or any other suitable means, and said stays may be slotted as at 17 to engage headed pins 18. The stays are normally forced in one direction by springs 19 and the slots 17 are curved or so arranged that in one position the stays will act as a lock and when forced against the springs 19 the case member 14 may be moved to its folded position.

20 A foldable support or member 20 is pivotally held to a transversely extending rod 21 which is supported in the sides of the main casing member 11 and at its forward end said foldable support 20 may be connected by a link 22 to the member 14 so that the member or support 20 may be folded with the member 14 of the case. The support 20 has sides 23 which may be connected by a transverse bar 24 and mounted in said support 20 is a segment 25. Type-bars 26 are pivoted to the segment in any suitable way, as to a rod 27, and said type-bars are adapted to carry a plurality of type and be supported at their outer end on a cushion 28, the latter being held to a cushion supporting frame 29 extending outwardly from and supported by the segment. The type-bars are each normally forced in one direction by springs 30 and are each connected by a link 31 to one arm of a bell-crank lever 32. Each bell-crank lever is pivotally held to a rod or support 33. There are four rods each being adapted to support a plurality of the levers 32. The bell-crank levers 32 each have one arm, as 34, provided with a cam edge 34^a which is adapted to engage a cam edge 35 of key-operated levers 36. These key-operated levers 36 are supported in groups or banks upon rods or supports 37 which are horizontally arranged in the normal operative position of the machine under the rods 33 and correspond in number to said rods 33. As each key is depressed the cam edge 35 will operate its co-operating bell-crank lever and through a link 31 will move the type-bar upwardly and rearward for printing purposes, and by reason of the arrangement in groups or banks a substantially uniform touch is obtained.

60 The platen carriage 38 may be of the usual or of any preferred form. As shown it comprises a rear guide or base 39, the upper and lower edges of which are each provided with a raceway which is opposed 65 to the raceway or track of transversely ex-

tending bars or members 40 and 41, both of which may be secured to a strengthening plate or member 42 held to the rear plate or wall of the main casing member 11. Balls or other anti-friction devices 43 are arranged in the raceways to adapt the bed and carriage to travel easily transversely of the machine. The carriage may have end plates 44 in which is mounted to rotate the usual platen or roll 45. The carriage may have the usual paper apron 46 and the usual finger knobs 47 for rotating the platen, and may also be provided with the usual or any preferred form of line-spacing means, paper fingers and other attachments usually employed in typewriting machines, but as such features form no part of the present invention it is thought unnecessary to describe or show them in detail.

Any suitable means may be provided as 85 an escapement and letter-spacing means for the carriage 38, it being necessary however, that provision be made whereby the folding principle involved will permit the operation of such escapement during the depression of 90 the keys for the printing operation, the letter-spacing movement taking place immediately after such printing operation or substantially instantaneously therewith. As 95 one escapement means and operating mechanism therefor, I provide a universal bar 48 which is suspended by arms 49, the latter being pivotally held at 50 on the type-bar segment 25. The universal bar 48 is adapted to be engaged by the rear cam edge 100 51 of the type-bars 26. The purpose of the cam edge 51 of the type-bars is to start the universal bar gradually during the upward and rearward movement of the type-bars and to give the universal bar an accelerated movement without altering the uniform character of the touch of the keys and in order that no sudden jar on the keys may be apparent to the operator when the type-bars start to actuate said universal bar. 110 A pair of upwardly extending arms 52 are fixed at their lower ends on a transversely extending rod 53 rotatably journaled at its ends in the sides of the support 20. The free upper ends of the rods 52 rest idly 115 against the rear surface of the universal bar 48. Arms 54 project forwardly from the rod 53 and said arms have their forward ends slotted to engage pins 55 carried by the inner ends of arms 56. The arms 56 are held to the transversely extending pivot rod 21 and serve, when the universal bar moves the arms 52, to rotate the pivot rod 21, the latter being rotatably held at its ends 120 in the side members of the main casing member 11.

The rod 21, Figs. 3 and 6, has a cam member 57 secured thereto near one end thereof adjacent to the outer surface of one of the sides of the support 20, and this cam mem-

ber is adapted to engage a slidable coöperating cam member 58. The cam member 57 has a substantially V-shaped portion 59 fitting a correspondingly shaped recess in the slidable non-rotating cam member 58, the latter being slidably held by a key or otherwise to a fixed sleeve 60 through which one end of the rod 21 passes, said cam member 58 being normally forced inwardly by means of a spring 61. The sliding cam member 58 is provided with an annular groove which is engaged by the forked end 62 of a lever 63. The lever 63 is substantially bell-crank shaped and is pivoted at 64 to a lug on one of the sides of the case member 11 and has its upper arm 65 extending inwardly and provided with a slotted or forked end 66 which is adapted to engage a pin 67 extending outward from a rod 68, so that on each movement of the lever 63 as will be presently described, the said rod 68 by means of the pin 67 will be rocked on its pivot pins or screws located at the ends thereof.

On the rod 68 are two dogs 69 and 70 the former being the loose or limber dog and the latter the fixed dog, and both dogs being adapted to rock back and forth with the partial rotary movement of the rod 68. The escapement dogs 69 and 70 are adapted to engage the teeth of an escapement wheel 71 the latter being loosely mounted on a headed stud 72. A ratchet wheel 73 at the rear of the escapement wheel 71 is engaged by the tooth of a pawl 74 and movable with the ratchet wheel is a pinion 75. The pinion 75 is in mesh with the teeth of a carriage rack 76, the said rack being secured to the carriage bed 39. The carriage has a flexible connection 77 attached thereto which passes around a pulley 78 and then about a spring drum 79 by which the carriage is kept under tension in the usual manner tending normally to drive the carriage across the machine in the usual way.

When the keys 80 of the levers 36 are depressed to force the type-bars to printing position the cam 51 of each type-bar will move the universal bar and this will rock the arms 52. The arms 52 will rock the shaft or rod 53 and move the arms 54 and this will rock the arms 56 on the pivot shaft 21 of the support 20. This rocking movement of the rod or shaft 21 will rock the cam member 57 and move the cam member 58 along said rod or shaft 21 against the tension of the spring 61 so as to move the lever 63 on its pivot 64. This will rock the rod 68 and will move the dogs therewith so that the tension of the spring in the drum 79 will by the usual action of the dogs permit the carriage to escape and move a single space at each depression. The pawl 74 will permit the carriage to be moved backward in the usual way for starting a new

line of writing without affecting any of the parts of the escapement mechanism and immediately the carriage is released the tension mechanism will again act through the escapement to permit the carriage to move across the machine a single space at every depression of a key 80.

In addition to the keys 80 forming a part of the keyboard and for letter spacing without printing a space-bar 81 is provided. This space-bar 81 is held to arms or brackets 82 which are pivoted at 83 to the ends of space arms or levers 84. The brackets 82 normally engage stops 85 so that on the depression of the bar 81 the space levers 84 will be operated by the pivotal brackets 82. The space-bar may be folded upward and over as shown in Fig. 4 to adapt the machine to be made more compact when in a folded and closed condition. The space levers 84 are pivoted to one of the transversely extended fulcrum rods 37 of the key-operated levers 36 and at their inner ends are bent downward so as to engage under the pins 55, said levers being restored to their normal position by means of one or more springs 86. As the space-bar is operated the levers 84 will be moved on their pivots to force the inner ends upward and by their engagement under the pins 55 will move the arms 56 as well as the arms 54 and by moving the arms 56 will rotate the rod or shaft 21 and through the cam members 57 and 58 already described will operate the escapement mechanism for letter spacing between words without printing as is the case in the ordinary typewriter.

It will be evident that when the support 20 is folded so that the keys of the keyboard are moved toward the platen 38 as shown in Fig. 4, the entire support 20 is located within the sides of the main casing member 11 so that the supporting case member 14 may form a partial closing of the case, said closing being completed when the cover member 12 is moved from the position shown in Fig. 1 to that shown in Fig. 4, a handle, not shown, being provided at the end of the case or other part thereof if desired for carrying purposes. It will be evident further that all parts mounted upon the foldable support 20 partake of the folding movement of the case member 14, so that not only the type basket including the type-bars but the entire key action partakes of such folding movement, and that all of these parts both in the folded and unfolded positions remain in the same operative relation and without any disconnection of any kind.

It will also be evident that simple means is provided whereby a part of a typewriting machine may be foldable with respect to another part to make the machine compact; that simple means is provided whereby the keyboard and those parts making the print-

ing mechanism may be independently mounted and movable with respect to other parts without any disorganization whatever; that simple escapement mechanism is provided; and that said escapement mechanism is adapted for typewriting machines whether employing an ordinary frame or wherein an inclosing case forms a supporting frame in which latter event the ordinary independent separate carrying case usually employed may be dispensed with.

It will be understood that any suitable ribbon mechanism may be employed as well as other features, but as they form no part of the present invention it was not thought necessary to either show or describe them herein.

Having thus described my invention, I claim as new and desire to secure by Letters Patent:

1. In a visible typewriting machine, the combination of a platen carriage, type-bars having an upward and rearward movement, key-operated levers forming a part of a universal keyboard and operatively connected to the type-bars, a foldable support on which the type-bars and key-operated levers are mounted and which partake of the foldable movement of said support, a universal bar movably held upon said foldable support, escapement mechanism normally maintained in a fixed relation to the platen carriage and adapted to permit said carriage to have letter-spacing movement, and means operatively connecting the universal bar to the escapement mechanism to adapt the escapement mechanism to be operated each time a key-operated lever is depressed and which permits the keys of the keyboard to be moved into close relation to the platen carriage and the coöperative relation between the universal bar and the escapement mechanism maintained.

2. In a typewriting machine, the combination of a platen carriage, type-bars, key-operated levers forming a part of a universal keyboard and operatively connected to the type-bars, a foldable support on which the type-bars and key-operated levers are mounted and which partake of the foldable movement of said support, a universal bar movably held upon said foldable support, escapement mechanism normally maintained in a fixed relation to the platen carriage and adapted to permit said carriage to have letter-spacing movement, and foldable means operatively connecting the universal bar to the escapement mechanism to adapt the escapement mechanism to be operated each time a key-operated lever is depressed and which permits the keys of the keyboard to be moved into compact relation to the platen carriage.

3. In a visible typewriting machine, the combination of a platen carriage, type hav-

ing an upward and rearward movement, key-operated levers forming a part of a universal keyboard and operatively connected to the type, a foldable support on which the type and key-operated levers are mounted and which partake of the foldable movement of said support, a universal bar, escapement mechanism for controlling the letter-spacing movement of the carriage, and foldable means operatively connecting the universal bar to the escapement mechanism to adapt the escapement mechanism to be operated each time a key-operated lever is depressed and which permits the keys of the key-board to be moved into vertical compact relation to the platen carriage and the coöperative relation between the universal bar and the escapement mechanism maintained without disconnection.

4. In a visible typewriting machine, the combination of a platen carriage, type-bars, key-operated levers forming a part of a universal keyboard and operatively connected to the type-bars, an upwardly foldable support on which the type-bars and key-operated levers are mounted and which partake of the foldable movement of said support, a universal bar, escapement mechanism normally maintained in a fixed relation to the platen carriage and adapted to control the letter-spacing movement of said carriage, and foldable means to adapt the escapement mechanism to be operated each time a key-operated lever is depressed and which permits the keys of the keyboard to be moved into compact relation to the platen carriage and the coöperative relation between the universal bar and the escapement mechanism maintained.

5. In a visible typewriting machine, the combination of supporting means, a platen carriage movable along said supporting means, a foldable support movable relatively to said supporting means, type, key-operated levers forming a part of a universal keyboard and operatively connected to said type to move the same toward the platen and mounted with the type upon said foldable support, a universal bar adapted to be operated as the keys are depressed, escapement mechanism for letter spacing the carriage, and a foldable non-separable operable connection between the universal bar and the escapement mechanism to adapt one part of said connection with the foldable support to be folded to place the keys of the keyboard in compact relation with the platen carriage when not in use.

6. In a visible typewriting machine, the combination of a platen carriage, a foldable support movable relatively to said platen carriage, type, key-operated levers forming a part of a universal keyboard and operatively connected to said type to move the same toward the platen and mounted with the

type upon said foldable support, a universal bar, escapement mechanism for letter spacing the carriage, and a two-part non-separable foldable mechanism operatively connecting the universal bar and the escapement mechanism, a part of said mechanism being mounted on said foldable support and foldable therewith.

7. In a visible typewriting machine, the combination of supporting means, a platen carriage movable along said supporting means, rotary escapement mechanism for letter spacing the carriage, a foldable support, a universal bar mounted upon said support, key-operated levers forming a part of a universal keyboard mounted upon said foldable support, type-bars one for each key-operated lever also mounted upon said support and adapted to operate the universal bar, and foldable and operative mechanism connecting the universal bar to the escapement mechanism.

8. In a visible typewriting machine, the combination of supporting means, a platen carriage movable along said supporting means, escapement mechanism for letter spacing the carriage, a foldable support, a universal bar mounted upon said support, key-operated levers forming a part of a universal keyboard mounted upon said foldable support, type-bars one for each key-operated lever adapted to actuate the universal bar, and foldable operative mechanism connecting the universal bar to the escapement mechanism, a part of said mechanism being mounted on said support.

9. In a visible typewriting machine, the combination of supporting means, a platen carriage movable along said supporting means, rotary escapement mechanism for letter spacing the carriage, a universal bar, key-operated levers forming a part of a universal keyboard, type-bars one for each key-operated lever adapted to actuate the universal bar, and non-separable foldable operative mechanism connecting the universal bar to the escapement mechanism.

10. In a visible typewriting machine, the combination of supporting means, a platen carriage movable along said supporting means, rotary escapement mechanism for letter spacing the carriage, a foldable support, a universal bar mounted upon said support, key-operated levers forming a part of a universal keyboard mounted upon said foldable support and adapted to have the keys moved toward the platen carriage when not in use, type-bars one for each key-operated lever adapted to actuate the universal bar, and foldable mechanism forming an operative connection between the universal bar and the escapement mechanism.

11. In a visible typewriting machine, the combination of supporting means, a platen carriage movable along said supporting

means, a rack carried by the carriage, a pinion engaging the teeth of said rack, a toothed wheel operatively connected to move the pinion, a shaft, dogs mounted on said shaft and adapted to engage said toothed wheel, tension mechanism tending to force the carriage in one direction, foldable key-operated levers forming a part of a universal key-board, type operatively connected to said key-operated levers, a type being adapted to make an impression as each individual key-operated lever is depressed, a foldable universal bar adapted to be moved as each key-operated lever is depressed, and foldable operative means arranged between the universal bar and said shaft carrying the escapement dogs.

12. In a visible typewriting machine, the combination of supporting means, a platen carriage movable along said supporting means, a rack carried by the carriage, a pinion engaging the teeth of said rack, a toothed wheel operatively connected to move the pinion, a shaft, dogs moved by said shaft and adapted to engage said toothed wheel, tension mechanism tending to force the carriage in one direction, key-operated levers forming a part of a universal keyboard, type operatively connected to said key-operated levers, a foldable universal bar adapted to be moved as each key-operated lever is depressed, and operative means arranged between the universal bar and said shaft.

13. In a visible typewriting machine, the combination of supporting means, a platen carriage movable along said supporting means, escapement dogs, a shaft to which said dogs are held, a bell-crank lever having one of its arms engaging a part of said shaft to move the same and having its other arm slotted, a sliding cam member having a grooved portion engaged by said slotted end of the bell-crank lever, a spring normally forcing said member in one direction, a rotary shaft extending transversely of the machine, a cam member held to said shaft and adapted to move the first-mentioned cam member against the tension of the spring to move the bell-crank lever and operate the dogs, arms projecting outward from said rotary shaft and provided with pins, a rod, arms having slotted ends held to said rod and engaging said pins, upwardly extending arms held to said rod, a pivotally held universal bar adapted when moved to move said last-mentioned arms and thereby rotate the cam member carrying shaft, and key-operated levers operatively connected to move the universal bar when depressed.

14. In a visible typewriting machine, the combination of a platen carriage, escapement dogs, a bell-crank lever having one of its arms adapted to move the dogs and hav-

16. In a visible typewriting machine, the combination of a platen carriage, escapement dogs, a bell-crank lever having one of its arms operatively connected to move the dogs, a sliding cam member adapted to operate said lever, a spring normally forcing said cam member in one direction, a rotary shaft extending transversely of the machine, a second cam member held to said shaft and adapted to move the first-mentioned cam member against the tension of the spring to move the bell-crank lever and operate the dogs, arms projecting outwardly from said rotary shaft, a rod, arms held to said rod and operatively connected to the arms of the rotary shaft, upwardly extending arms held to said rod, a pivotally held universal bar adapted when moved to move said arms and thereby rotate the cam member carrying shaft, and key-operated levers operatively connected to move the universal bar. 70
10. 15. In a typewriting machine, the combination of a platen carriage, escapement dogs for letter spacing the carriage, a movable cam member operatively connected to move the dogs, a rotary shaft extending transversely of the machine, a cam member held to said shaft and adapted to move the first-mentioned cam member and operate the dogs, a universal bar, connections between the universal bar and the rotary shaft to rotate said shaft and means for operating the universal bar. 75
20. 16. In a visible typewriting machine, the combination of a platen carriage, escapement dogs, a shaft to which the dogs are held, a bell-crank lever having one of its arms engaging a part of said shaft to move the same and having its other arm slotted, a sliding cam member having a grooved portion engaged by said slotted end of the bell-crank lever, a spring normally forcing said member in one direction, a rotary shaft extending transversely of the machine, a cam member held to said shaft and adapted to move the first-mentioned cam member against the tension of the spring to move the bell-crank lever and operate the dogs, a pivotally held universal bar operatively connected to rotate the cam member carrying shaft, and key-operated levers operatively connected to move the universal bar when depressed. 80
25. 17. In a visible typewriting machine, the combination of a platen carriage, escapement dogs, a rotary shaft extending transversely of the machine, means operated by said shaft for moving the dogs, arms projecting outwardly from said rotary shaft and provided with pins, a rod, arms having slotted ends held to said rod and engaging said pins, upwardly extending arms held to said rod, a universal bar adapted when moved to move said last-mentioned arms and thereby rotate said shaft, and key-operated levers operatively connected to move the universal bar when depressed. 85
30. 18. In a visible typewriting machine, the combination of a platen carriage, escapement dogs, a bell-crank lever having one of its arms operatively connected to move the dogs, a sliding cam member adapted to operate said lever, a spring normally forcing said cam member in one direction, a rotary shaft extending transversely of the machine, a cam member held to said shaft and adapted to move the first-mentioned cam member, a pivotally held universal bar, means movable by said universal bar to rotate the cam member carrying shaft, and key-operated levers operatively connected to move the universal bar when depressed. 90
35. 19. In a visible typewriting machine, the combination of a platen carriage, escapement mechanism including dogs for controlling the letter-spacing movement of said platen carriage, a foldable support, a universal bar suspended on said support, key-operated levers forming a part of a universal keyboard mounted on said support, type-bars, one for each key-operated lever adapted to move the universal bar and operatively connected to the key-operated levers, arms idly engaging the universal bar and adapted to be moved thereby when the keys are depressed to operate the type-bars, a rotary shaft forming a pivotal means 95 for said support, operating connections between the arms and said shaft, together with operative connections between the shaft and the escapement mechanism and constructed to maintain coöperative relation between 100 said shaft and the escapement mechanism when said support is in its folded and in its unfolded positions. 105
40. 20. In a visible typewriting machine, the combination of a platen carriage, escapement mechanism including dogs for controlling the letter-spacing movement of said platen carriage, a foldable support, a universal bar suspended on said support, key-operated levers mounted on said support, type-bars, one for each key-operated lever, operatively connected to said levers, arms idly engaging the universal bar and adapted to be moved thereby when the keys are depressed to operate the type-bars, a rotary shaft forming a pivotal means for 110 said support, connections between the arms and said shaft for rotating the shaft, together with operative connections between the shaft and the escapement mechanism 115 adapted to actuate the escapement mechanism when the shaft is rotated. 120
45. 21. In a visible typewriting machine, the combination of a platen carriage, escapement mechanism for controlling the letter-spacing movement of said carriage, a foldable support, a universal bar, key-operated levers mounted on said support, type-bars, one for each key-operated lever, operatively connected to said levers, arms moved by the 125 130

- universal bar, said bar being adapted to be moved when the keys are depressed to operate the type-bars, a rotary shaft forming a pivotal means for said support, operating connections between the arms and said shaft, together with operative connections between the shaft and the escapement mechanism adapted to actuate the escapement mechanism when the shaft is rotated.
22. In a visible typewriting machine, the combination of a platen carriage, escapement mechanism including dogs for controlling the letter-spacing movement of said platen carriage, a foldable support, a universal bar mounted on said support, key-operated levers forming a part of a universal key-board and mounted on said support, type-bars, one for each key-operated lever adapted to move the universal bar and operatively connected to the key-operated levers, a rotary shaft forming a pivotal means for said support, operative connections between the universal bar and said shaft for rotating the shaft, together with operative connections between the shaft and the escapement mechanism.
23. In a visible typewriting machine, the combination of a platen carriage, escapement mechanism including dogs for controlling the letter-spacing movement of said platen carriage, a foldable support, a universal bar suspended on said support, key-operated levers, type-bars, one for each key-operated lever mounted on said support and operatively connected to the key-operated levers, a rotary shaft forming a pivotal means for said support, means actuated by the universal bar for rotating said shaft, together with operative connections between the shaft and the escapement mechanism.
24. In a visible typewriting machine, the combination of a platen carriage, escapement mechanism controlling the letter-spacing movement of said platen carriage, a foldable support, a universal bar mounted on said support, key-operated levers forming a part of a universal keyboard mounted on said support, type-bars, one for each key-operated lever adapted to actuate the universal bar operatively connected to the key-operated levers, and foldable mechanism forming a connection between the universal bar and the escapement mechanism, the point of folding of said mechanism corresponding to the point of folding of said support.
25. In a visible typewriting machine, the combination of a platen carriage, escapement mechanism for controlling the letter-spacing movement of said platen carriage, a foldable support, key-operated levers forming a part of a universal key-board mounted on said support, type-operatively connected to the key-operated levers, a rotary pivotal means for said support, spacing levers pivotally held to said support and having their inner ends arranged to rotate said shaft when depressed, a foldable space-bar carried by said levers adapted when depressed to rotate said shaft, and operative connections between the shaft and the escapement mechanism to adapt the escapement mechanism to be operated by the space-bar.
26. In a visible typewriting machine, the combination of a platen carriage, escapement mechanism for controlling the letter-spacing movement of said platen carriage, a foldable support, key-operated levers mounted on said support, type-operatively connected to the key-operated levers, a rotary element, spacing levers pivotally held to said support, means operated by the spacing levers to rotate said element when depressed, and operative connections between the rotary element and the escapement mechanism to adapt the escapement mechanism to be operated by said spacing levers.
27. In a typewriting machine, the combination of a platen carriage, escapement mechanism for controlling the letter-spacing movement of said platen carriage, a foldable support, a rotary shaft forming a pivotal means for said support, a foldable space-bar mounted on said support, means operated by said bar to rotate the shaft, and operative connections between the shaft and the escapement mechanism to adapt the escapement mechanism to be operated by the space-bar.
28. In a typewriting machine, the combination of supporting means, a platen carriage movable along said supporting means, escapement mechanism for letter-spacing the carriage, a foldable support, key-operated levers mounted upon said foldable support, a universal bar mounted on the foldable support, type-bars operatively connected with the key levers and adapted to actuate the universal bar, and means connecting the universal bar and escapement mechanism for actuating the escapement, said means maintaining an operative connection between the escapement mechanism and the universal bar at all times.
29. In a typewriting machine, the combination of supporting means, a platen carriage movable along the supporting means, escapement mechanism for letter-spacing the carriage, a foldable support, key-operated levers mounted upon the foldable support, a universal bar mounted upon the foldable support, type-bars operatively connected with the key levers and mounted on said foldable support, said type bars being adapted to actuate the universal bar when the key levers are operated, and means connecting the universal bar and escapement mechanism for actuating said escapement mechanism, said means maintaining an op-

erative connection between the universal bar and the escapement mechanism at all times.

30. In a typewriting machine, the combination of supporting means, a platen carriage movable along the supporting means, escapement mechanism mounted on said supporting means for letter-spacing the carriage, a foldable support, key-operated levers mounted upon said foldable support, a universal bar mounted upon said foldable support, type-bars operatively connected with the key levers and mounted on said foldable support, and means connecting the

10 universal bar and escapement mechanism for actuating the escapement mechanism when the key levers are operated, said means maintaining an operative connection between the escapement mechanism and the 15 universal bar at all times.

31. In a typewriting machine, the combination of supporting means, a platen carriage movable along the supporting means, escapement mechanism mounted on said supporting means for letter-spacing the carriage, a foldable support, key-operated levers mounted upon the foldable support, a universal bar mounted upon the foldable support, type-bars operatively connected 25 with the key levers and mounted on said foldable support, said type bars being adapted to actuate the universal bar when the key levers are operated, and means connecting the universal bar and escapement 30 mechanism for actuating said escapement mechanism; said means maintaining an operative connection between the universal bar and the escapement mechanism at all times.

32. In a typewriting machine, the combination of a frame, a platen carriage movable in said frame, escapement mechanism including escapement dogs, a lever operatively connected to move the dogs, a rotatable shaft extending transversely of the 40 machine and supported in said frame, a cam fixed on said shaft, a coöperating cam slidably mounted on said shaft and adapted to actuate said lever, a universal bar, key-operated levers operatively connected to 45 move the universal bar when depressed, a support for the universal bar and key levers loosely pivoted on said shaft and adapted to swing about said shaft to enable the support and frame to be folded relatively 50 to each other, and means operated by the universal bar to rotate said fixed cam.

33. In a visible typewriting machine, the combination of a platen carriage, escapement mechanism including dogs for controlling the letter-spacing movement of said platen carriage, a foldable support, a universal bar suspended on said support, key-operated levers forming a part of a universal keyboard mounted on said support, 60 type-bars, one for each key-operated lever

adapted to move the universal bar and operatively connected to the key-operated levers, arms idly engaging the universal bar and adapted to be moved thereby when the keys are depressed to operate the type-bars, a 70 rotary shaft forming a pivotal means for said support, operating connections between the arms and said shaft for rotating said shaft, together with operative connections between the shaft and the escapement mechanism actuated by the rotation of the shaft and constructed to maintain coöperative relation between said shaft and the escapement mechanism when said support is in its folded and in its unfolded positions. 75

34. In a typewriting machine, the combination of a frame, a platen carriage movable in said frame, escapement mechanism supported in the frame, a foldable support, a universal bar mounted in said support, 80 key-operated levers mounted on said support, type bars operatively connected to said levers, a rotary shaft journaled in the frame, said support being loosely connected with the shaft and adapted to swing about 85 said shaft as a pivot, arms fixed on said shaft and adapted to be moved by said universal bar when the key levers are actuated, and means operatively connecting the shaft and the escapement mechanism to actuate 90 the escapement mechanism when the shaft is rotated by said arms, said means maintaining an operative connection between the rotary shaft and the escapement mechanism 95 at all times.

35. In a typewriting machine, the combination of a frame, a platen carriage movable in said frame, escapement mechanism supported in said frame, a rotatable shaft journaled in said frame transversely of the machine, key-operated levers, a universal bar adapted to be actuated when said levers are depressed, a foldable support for the key levers and universal bar loosely pivoted on said shaft, means actuated by the universal 100 bar for rotating said shaft, and means operated by the rotation of said shaft for actuating the escapement mechanism.

36. In a typewriting machine, the combination of a frame, a platen carriage movable in said frame, escapement mechanism supported in said frame, a rotatable shaft journaled in said frame transversely of the machine, key-operated levers, a universal bar adapted to be actuated when said levers are depressed, a foldable support for the key levers and universal bar loosely pivoted on said shaft, means actuated by the universal bar for rotating said shaft, said means maintaining an operative connection 115 at all times, and means operated by the rotation of said shaft for actuating the escapement mechanism, said means maintaining an operative connection between the shaft and escapement mechanism at all times. 120

37. In a typewriting machine, the combination of a support, a platen carriage mounted on the support, escapement mechanism mounted on the support, a foldable keyboard, a universal bar foldable with the keyboard, a lever pivotally held to the support intermediate its ends and operatively connected to actuate the escapement mechanism, two relatively movable cam mem-

bers, one of which has a foldable connection 10 with said lever, and means operated by the universal bar for causing a relative movement between said cam members for actuating the lever.

This specification signed this Nov. 20th, 15
1915.

CHARLES PHILO MOSHER.
